(57) **CLAIM**

The ornamental design for a docking module, as shown and described.

DESCRIPTION

FIG. 1 is a perspective view of a docking module; FIG. 2 is a top view of the docking module of FIG. 1; FIG. 3 is a front view of the docking module of FIG. 1; FIG. 4 is a side view of the docking module of FIG. 1; FIG. 5 is a side view of the docking module of FIG. 1; FIG. 6 is a rear view of the docking module of FIG. 1; and, FIG. 7 is a bottom view of the docking module of FIG. 1. The broken line showing of environmental structures is for illustrative purposes only and forms no part of the claimed design.
